CLAIM

The ornamental design for a rope cleat for power boat or the like, as shown and described.

DESCRIPTION

FIG. 1 is a front elevation view of a rope cleat for power boats or the like showing my new design;

FIG. 2 is an end elevation view thereof;

FIG. 3 is a top plan view thereof;

FIG. 4 is a bottom plan view thereof.

The opposite views are identical to those shown in FIGS. 1-2.

FIG.1

FIG.2

FIG.3

FIG.4
